UNITED STATES PATENT OFFICE.

JOHN RANDALL GOLDSWAITE, OF ATLANTA, GEORGIA.

ELECTRIC HEATER.

1,331,496.

Specification of Letters Patent. Patented Feb. 24, 1920.

Application filed December 4, 1915, Serial No. 65,022. Renewed June 18, 1919. Serial No. 305,183.

To all whom it may concern:

Be it known that I, JOHN R. GOLDSWAITE, a citizen of the United States, and a resident of Atlanta, in the county of Fulton and State of Georgia, have invented a new and Improved Electric Heater, of which the following is a full, clear, and exact description.

My invention relates to electric heaters. 10 The object of the invention is to provide a simple and inexpensive heating device primarily intended for melting wax when sealing and whereby the melting can be done on the spot where the seal is to be formed.

15 The subject matter of this invention is an improvement over my pending application, Serial No. 46,095, filed August 18, 1915.

Reference is to be had to the accompanying drawings, forming part of the specification, in which like characters indicate 20 corresponding parts in all the views.

Figure 1 is an elevation of the device, the novel part thereof being in section to show the details of construction;

25 Fig. 2 is a horizontal section on line 2—2, Fig. 1;

Fig. 3 is a fragmentary perspective view of the resistance carrying member; and

Fig. 4 is a perspective view of the stand 30 for the heater.

Referring to the drawings, 4 represents the handle of the casing wherein a circuit-closing switch is provided, a button 5 of which is countersunk in the handle, as shown 35 in dotted lines in Fig. 1, and whereby the switch may be closed when desired. The handle 4 flares out into a cup-shaped head 7 and with which it forms the casing. The head is lined across the top and along the 40 wall with a thermoelectric insulator 8. The insulator lining necessarily forms an insulator cup within the head of the casing, the bottom of said insulator cup preferably forming a concave paraboloidal surface to 45 which a paraboloidal reflector 9 is secured. A metallic reflecting surface preferably lines the lateral surface of the insulator 8.

The bottom of the head 7 projects below 50 the insulator lining 8 to receive an annular bottom casing 11 of channeled cross section and filled with thermoelectric insulator 12. Any suitable means 13 may be provided for securing the casing 11 to the head 7. Lugs 14 of a thermoelectric insulator ring 15 are 55 anchored within the insulator mass 12 of the casing so that the bottom of the ring 15 is

spaced from the casing. The diameter of said ring 15 is greater than the diameter of the opening in the annular casing 11 and concentric therewith. Said ring 15 has a 60 gap 16 whereat the ring has lugs 17. To each lug one end of an electric resistance element 18 is anchored. The ring has the cross section of an I beam. Notches 19 are provided at the corners of the upper and 65 lower surface of the beam for the resistance element 18 whereby the coils formed on the ring are properly spaced from each other.

Each end of the resistance element 18 is 70 in electrical connection through the medium of a screw 20 with a socket 21 embedded in the insulator 12 of the casing 11. Each socket has an extension forming a plug 22 above the surface of the insulator 12. A 75 suitable socket 23 is set into the end of the insulator lining 8 for receiving the plug 22. Each of said sockets 23 are connected by a lead 24 to the switch in the handle. The engagement between the socket 23 and the 80 plug 22 takes place when the casing 11 is secured to the head 7 of the main casing. It will be noted that whenever the bottom casing 11 is removed from the head the resistance element will be removed therewith, 85 since the same is anchored to said casing. This affords an easy inspection of the main parts of the device and an easy change in the heating elements if necessary.

The heat generated by the current passes 90 through the electric resistance, radiates to the reflector 9, from where it is reflected through the opening in the bottom casing 11. If a wafer of wax is placed in the sphere of action of the heat rays coming 95 from the reflector the wax will melt, and particularly if it is placed adjacent the focus of the reflector, which is in close proximity to the bottom of the heater, as indicated in dotted lines in Fig. 1. With my device a 100 wax wafer can be melted at any desired spot without bringing the heating device in contact with the wafer and the surface on which the wax is to be melted. The top of the handle 4 is adapted to receive a die 105 to impress the wax melted by the device.

The handle 4 of the device has a collar 25 at the upper end thereof whereby the device can be suspended on a stand which comprises a bracket 26 rising from a base 27, 110 the sides of the brackets having substantially the contour of the sides of the device.

The top of the bracket has a semi-circular recess 28 in the plane with the top for admitting the device centrally on to the bracket, the part of the bracket forming the recess making a rest for the collar 25, whereby the device is suspended on the stand. An asbestos pad 29 is provided on the base to prevent the stand from absorbing the heat accumulated by the device during the use thereof.

I claim—

1. In a device of the class described, a casing having a cup-shaped head, insulator means lining the head, an annular bottom casing secured to the head, an electric resistance within the head and carried by said bottom casing, a reflector within the head adapted to reflect the heat radiated thereupon from the electric resistance through the annular bottom casing, and means controlling the supply of current to said electric resistance.
2. In a device of the class described, a casing having an enlarged cup-shaped head, insulator means lining the head, an annular bottom casing secured to the head, an insulator ring having the cross section of an I beam carried by said bottom casing so that the same is spaced from said casing, said ring having a gap, an electric resistance wound about said ring, a reflector associated with the insulator of the head for directing the heat radiated upon it through the annular bottom casing, and means for controlling the supply of current to said electric resistance.
3. In a device of the class described, a casing having an enlarged cup-shaped head, insulator means lining the head, an annular bottom casing secured to the head, said bottom casing being of channeled cross section, insulator means in said casing, an insulator ring having lugs embedded in the insulator within the bottom casing whereby said ring is maintained concentric with the annular casing and spaced therefrom, said ring having a gap and the cross section of an I beam, an electric resistance wound about said ring, means for controlling the supply of current to said resistance, and a reflector carried by the insulator lining of the head for reflecting the heat from the electric resistance through the annular bottom casing.
4. In a device of the class described, a casing having a cup-shaped head, insulator means lining the head, an annular bottom casing of channeled cross section adapted to be secured to the head, insulating means carried by said casing, switch plugs embedded in said insulating means, switch sockets carried by the insulator lining of the head and adapted to be engaged by said plug when said annular bottom casing is secured to the

head, a ring of insulating material having lugs embedded in the insulation within the bottom casing and whereby said ring is maintained concentric with the bottom casing and spaced from said bottom, said ring having a gap and having in cross section the shape of an I beam, an electric resistance wound about said ring and in electrical connection with the plugs, and a switch in said handle in electrical connection with the sockets and whereby the current through the electrical resistance is controlled, and a reflector associated with the insulator lining for directing the heat rays through the annular bottom casing.

5. A portable device for heating wafers of sealing wax and the like, comprising a substantially annular electrical heating element, a suitable support for said element, a casing surrounding said element and support and having an opening in its under side, and a reflector within the casing and above said heating element adapted to direct the heat rays through said opening and converge them upon a wafer or other objects to be heated.

6. In a device for heating wafers of sealing wax and for similar purposes, the combination of a casing having an opening in the under side thereof, an electric resistance element in said casing symmetrically arranged with respect to and above said opening, and a reflector in said casing opposite said opening and back of said resistance element for converging the heat rays at a point below the casing.

7. A device for heating wafers of sealing wax, comprising a casing having a substantially circular opening in one side thereof, an electric resistance element in said casing, symmetrically arranged with respect to and above said opening, and a reflector in said casing opposite said opening and back of said resistance element and adapted to reflect the heat rays through said opening and converge them at a point outside the casing.

8. In an electric heating device, the combination of a hollow casing comprising complementary members and having a heat reflecting surface on the interior thereof, and an electrical resistance element in said casing, said casing having an opening in the wall thereof opposite said reflecting surface whereby heat generated by said resistance element will be reflected out of the casing through said opening.

In testimony whereof I have signed my name to this specification in the presence of two subscribing witnesses.

JOHN RANDALL GOLDSWAITE.
